ADJUSTABLE TELESCOPING SPREADER

Harold Warren, P.O. Box 413, Springfield, Ohio

Filed May 22, 1957, Ser. No. 660,827

5 Claims. (Cl. 94—44)

This invention relates to a device for the dispensing and spreading of paving and road building materials such as hot or cold mixes, crushed rock, gravel and similar aggregates.

A primary object of the invention is to provide a paving material dispenser device which is laterally adjustable from the ends of the device for regulating the width of dispensed material. Such a dispenser is desirable in connection with the paving of driveways and similar situations, where it is frequently advantageous to be able to change the width of the paving material dispensed as the operation progresses. Further the device of invention provides for the formation of tapered driveways as lateral adjustment may take place continuously, or as required, to vary the width of the paving material spread.

A particular object of the invention is to provide in conjunction with a telescoping hopper arrangement a telescoping screed which provides for the spreading of material dispensed from the hopper in the same width as that dispensed by the hopper.

Yet another object of the invention is the provision of a dispenser device for paving materials which device is adjustable laterally from each end thereof and which is supported from the adjustable ends in such manner that a central support is not necessary.

In the device of invention forward and rearward stationary wall members of the structure disposed intermediate the width of the apparatus receive in telescoped relation and are supported by end closure units which, with the stationary wall members, complete the hopper. Support of the stationary wall members is provided along the forward and rearward walls by the end closure units which are themselves supported above ground level by any suitable means which are adapted for towing of the device, for example. The support means of the stationary wall members are suitably formed to house drive elements for occasioning movement of the telescoping end closure units relative to the stationary wall members.

A screed extends along the rearward wall of the spreader and has telescoping portions which are pivotally connected to the closure units and movable therewith as well as in a vertical plane. Independent screed adjustments provide for controlled screed movement of tapered pavings.

These and other objects of the invention will be more fully understood by reference to the following detailed description and accompanying drawings wherein:

Figure 1 is a perspective view of the device of invention taken from a forward side thereof;

Figure 2 is a rear view of the device of invention with supporting members removed and showing the device in a position of minimum width, portions being broken away for completeness of illustration;

Figure 3 is a view similar to that of Figure 2 but illustrating the device in a position of extended width, portions being broken away for completeness of illustration;

2

Figure 4 is a sectional view taken approximately on line 4—4 of Figure 1;

Figure 5 is a sectional view taken substantially on line 5—5 of Figure 2;

Figure 6 is a fragmentary view, somewhat enlarged, illustrating a screed supporting arrangement; and

Figure 7 is a sectional view taken on line 7—7 of Figure 2.

In the device of the drawings the opposed lateral hopper closure telescoping ends and the arrangements thereof are similar and accordingly for convenience reference in detail will be made to only one end.

In Figure 1 the numeral 1 designates a forward stationary wall member which extends laterally of the device over a major portion of the length thereof and which tapers downwardly inwardly of the hopper rearwardly. The numeral 3 designates the rear stationary wall member of the hopper which extends laterally in parallel relation with the wall member 1 and is of the same length as the stationary wall member 1. Stationary wall members 1 and 3 are spaced apart and define an open hopper bottom 5 through which paving materials are distributable to a roadbed. Stationary wall member 1 is flanged at 7 (Figure 4) over the length thereof and stationary wall member 3 is similarly flanged at 9.

The numeral 11 generally indicates a hopper end closure which is provided with an end panel 13 to which are welded side panels 15, 17. Side panels 15, 17 are flanged respectively at 19, 21. The end closure unit 11 (Figure 1) is telescoped over one end of the stationary wall members 1, 3, connects these members together, and with the members forms one end of the dispenser device. The provision of the second and similar end closure unit 11 at the further end of the device completes the hopper.

The panels 15, 17 of the closure unit 11 lie along the inner side of the stationary wall members 1, 3, respectively, while the flanges 19, 21, respectively, engage over the flanges 7, 9 of the stationary wall members 1, 3.

As shown in Figure 1 along the forward stationary wall member there is provided a channel 23 which extends over substantially the full length of the stationary wall member in parallel relation with a similar lower channel 25. Each of the channels is suitably welded or otherwise secured to the forward stationary wall member. A similar pair of channels 27, 29 are provided on the rearward stationary wall member 3.

The panel 15 of the end closure member 11 is provided at its extremity at 31 with a metal pad welded thereto. Secured on this pad suitably by welding is a somewhat smaller channel member 33 which telescopes within the channel member 23. Similarly, channel member 35, also secured on the pad 31, telescopes within the channel member 25. On the rearward side of the device a similar pad 37 has welded thereto an extremity 55 of a channel 39 which telescopes within the channel 27. The pad 37 also supports at its lower end another channel 41 which telescopes within the channel 29.

The pads 31, 37 project from the outer surface of the panels and abut the ends of the stationary wall members in the closed position of the dispenser device shown in Figure 2.

The channels 33, 35, 39, 41 are somewhat longer than half of the length of the channels on the stationary wall members and accordingly extend substantially to the center of the width of the device in the closed position thereof.

As already noted and as shown in the drawings similar channels are provided on the second end of the device and will extend closely into adjacent relation with the channels 33, 35, 39, 41 in the closed position.

Extending into each of the channels carried by the telescoping end closure units is a threaded screw, such

being designated at 42, 43, 44, 45, respectively. These screws cooperate with appropriately positioned nuts 46, 47, 48, 49 secured on the stationary wall members 1 and 3, respectively, within the channels. Suitably the channels are packed with grease both to facilitate screw operation and relative sliding of the channels.

Projections 50, 51, 52, 53, respectively, of the screw threads extend laterally beyond the end of the device and receive the sprockets 54, 55, 56, 57. Approximately centrally of the panel 13 a fifth sprocket 58 is mounted for free rotation to serve as an idler.

A chain 60 passes over the sprockets (Figure 1); projection 52 has secured thereto a handle 61 for driving of the chain and accordingly for turning of the screw threaded shafts simultaneously in rotation.

A similar structural arrangement is provided at each end of the device and accordingly each end closing unit is separably adjustable laterally to provide for the dispensing of variable widths of paving material.

An angle reinforcement 63 is welded to the panel 13 and the flanges 19, 21 and to the vertical standard 65. The standard 65 is itself secured by welding to a skid 67. A pair of such skids provide support for the end closure units and consequently for the stationary wall members which are supported by the end closure members above ground level. The skids also furnish means which are adapted for towing of the dispenser. The skid 67 is also welded at 68 to the bottom extension of panel 13. Other common movable support means may be used in place of the skids.

The numeral 69 indicates a connecting bar which is pivotally secured at one end to a stub shaft 71 welded to the hopper end closure. The other end of connecting bar 69 is pivotally secured to a rod 73 which is itself secured on a screed generally designated at 75 and shaped as shown in Figure 6.

A pair of washers 76, 77 on either side of the connecting bar 69 and welded to the rod 73 retain the bar 69 in position endwise of the device. The screed 75 (Figure 2) has a stationary portion 79 and is hollow to provide for the receipt therein of a telescoping portion 81. This telescoping portion 81 is also hollow as is indicated in Figure 6, but the end is normally closed by a suitable plate welded thereto as shown in Figure 1. The telescoping portion 81 is the portion of the screed to which the rod 73 is secured. Accordingly, upon movement of the end closure 11 the bar 69, rod 73 and the screed telescoping portion 81 will move as a unit laterally. As already noted a similar structural arrangement is prepared for the opposite end of the device; thus the screed is supported for pivotal movement from the ends of the closure units.

The screed 75 is spaced slightly from the rear wall 3 and a guide 83 on the channels 27, 29 extends vertically and tends to assist in the maintaining of the spacing. The screed 75 is vertically adjustable through the medium of a threaded screw rod 85. Threaded rod 85 carries on its upper end handle 87 and its lower end projects into a fixed nut 89 mounted within a shell casing 91 on the fixed portion of the screed.

Upwardly the shaft 85 is supported from the fixed portion of the stationary wall member 3 by a suitable bracket 93. Similar screw shafts 85 are provided at each end of the device for movement of the screed. However, one end of the screed may suitably be at a slightly higher level than the other due to the inherent resiliency of the structure, thus providing for a tapered effect in the height of the dispensed material.

Referring again to Figure 1, the numeral 95 generally designates a hitch having rubber tired wheels 96 and which hitch is adapted to connect the dispenser spreader to the rear axle of a truck, for example. Any suitable type of connecting means between the spreader and towing vehicle may be employed however. For the purpose of elevating the hitch 95 there is provided on the rear of

the spreader 97 a hand pump 98 having a handle 99. This pump is connected through a hose connection 101 with an operative pressure cylinder mechanism 103 of the hitch 95; such provides for raising and lowering the hitch to permit the hitch to engage the rear axle of a truck, for example.

As shown in Figure 1 the hose 101 is protected in its passage from the rear to the front of the spreader by suitable piping 105 through which the hose passes.

Hooked portions 107 are suitably provided on the respective ends of the hitch for drawing of the spreader by engagement of the hooks with an axle, for example, and whereby the hitch and spreader are directed or steered. Hooks 109 are conveniently provided on the forward side of the spreader for attachment of chains (not shown) for manipulation of the spreader as required as, for example, in pulling the spreader to a location to be paved. Also as illustrated in Figure 1 the hitch may be retained upwardly for towing of the assembly to a location to be paved by chains extending from the forward stationary wall member to the hitch.

Summarizing the operation briefly, rotation of the handle 61 causes threaded screws 42, 43, 44, 45 to rotate in unison through their respective nuts 46, 47, 48, 49, and to cause the end closure unit 11 to move inwardly and outwardly of the stationary members, depending upon direction of rotation of the handle 61. Simultaneously the telescoping portion 81 of the screed is moved with the end closure 11. Adjustment of the vertical screed height to provide a uniform surface or a slightly tapered surface may be made either before or during movement of the end portion.

It is to be particularly noted that the stationary wall members of the device of invention are supported from the movable end closure units by structural elements extending along the lateral walls of the spreader device. Such arrangement is economical of dispensing space and adapts the device for utilization in situations where the paving material must be spread close to abutments such as walls and the like.

While in the specific description the actuating means which connect the telescoping sections with the stationary walls have been illustrated as threaded screws, a similar mode of operation may be effected with hydraulic means for example. Screws are somewhat advantageous relative to economy of structure however. The screws in essence not only aid in supporting the stationary members, but they normally restrain the end closures against movement relative to the stationary walls even under a full load on the device.

It will be understood that this invention is susceptible to modification in order to adapt it to different usages and conditions and accordingly, it is desired to comprehend such modifications within this invention as may fall within the scope of the appended claims.

I claim:

1. In a portable dispensing and spreading device, the structure comprising, a hopper having forward and rearward stationary wall members extending laterally of the device in spaced apart relation to form hopper opening, the forward stationary wall member extending downwardly rearwardly toward the rearward stationary wall member, a pair of channels on the forward stationary wall member extending the length of the forward stationary wall member and provided in vertically spaced relation, a pair of channels on and extending the length of the rearward stationary wall member and provided on the rearward stationary wall member in vertical spaced relation, an end closure unit connecting adjacent ends of the forward stationary and rearward stationary wall members together and having forward and rearward panels which telescope with the forward stationary and rearward stationary wall members, said panels each having a pair of channels which telescope within channels of the stationary wall members and which form supporting means for the

stationary wall members, a nut within each channel of the stationary wall members and secured to the stationary wall, a screw cooperable with each nut and extending axially of the channels, a sprocket on the extremity of each screw, a chain connecting the sprockets, and manipulable means on one screw for effecting rotation of the screws and sprockets manually whereby said screws are moved in unison to provide telescoping movement of the end closure unit on the stationary wall members.

2. In a portable dispensing and spreading device, the structure comprising, a hopper having forward and rearward stationary wall members extending laterally of the device in spaced apart relation to form a hopper opening, said hopper having end closure units, means secured to the end closure units supporting the hopper above ground level, a pair of channels on the forward stationary wall member extending substantially the length of the forward stationary wall member and provided in vertically spaced relation, a pair of channels on and extending substantially the full length of the rearward stationary wall member and provided on the rearward stationary wall member in vertically spaced relation, one said end closure unit connecting adjacent ends of the forward stationary and rearward stationary wall members together and having forward and rearward panels which telescope with the forward and rearward stationary wall members, said panels, each having a pair of channels which telescope with said channels of the stationary wall members and which form supporting means for the stationary wall members, and cooperable but separate drive means for effecting lateral movement of the one said end closure unit and the channels thereof relative to the stationary wall members and their channels, the said cooperable but separate drive means including in association with each of the telescoping channels and channel members cooperating relatively movable elements, one of which is carried by a stationary wall member and the other of which is carried by a panel of the said end closure unit, and means interconnecting the separate drive means for effecting movement of the cooperable but separate drive means in unison.

3. In a paving material dispensing device which is adjustable laterally for regulating the width of a dispensing material, the structure comprising, forward and rearward stationary wall members extending laterally of the device in spaced-apart relation, hopper end closure units having panels telescoped on the stationary wall members at each end thereof forming with the stationary wall members a hopper, means supporting the hopper above ground level, said means being secured to the end closure units in supporting relation therewith, a channel on the forward stationary wall member on the outer hopper side extending laterally of the device substantially the full length of the forward stationary wall, a channel on the rearward stationary wall member on the outer hopper side extending laterally of the device substantially the full length of the rearward stationary wall member, the said panels of at least one of the said end closure units being slidable on the sides of the forward and rearward stationary wall members laterally of the device and each panel of the one said end closure unit having an extremity extending laterally of the device beyond the stationary wall members, each said extending panel of the one said end closure unit having a channel and means supporting and aligning the channel with a channel of a stationary wall member and which channels of the panels telescope within the channels of the stationary wall members and form support means for the stationary wall members, and cooperable but separate drive means for effecting lateral movement of the panels and channels of at least the one said end closure unit relative to the stationary wall members and the channels of the stationary wall members, said cooperable but separate drive means including in association with each of the telescoping channels and channel members cooperating relatively

movable elements, one of which is carried by a stationary wall member and the other of which is carried by a panel of the said end closure unit, and means interconnecting the separate drive means for effecting movement of the cooperable but separate drive means in unison.

4. In a paving material dispensing device which is adjustable laterally for regulating the width of a dispensing material, the structure comprising, forward and rearward stationary wall members extending laterally of the device in spaced-apart relation, hopper end closure units having panels telescoped on the stationary wall members at each end thereof forming with the stationary wall members a hopper, means supporting the hopper above ground level, said means being secured to the end closure units in supporting relation therewith, an outer channel on the forward stationary wall member on the outer hopper side and extending laterally of the device substantially the full length of the stationary wall member, an outer channel on the rearward stationary wall member on the outer hopper side and extending laterally of the device substantially the full length of the rearward stationary wall member, the said panels of the said end closure units being slidable on the inner side of the stationary wall members laterally of the device and each panel of the said end closure units having an extremity extending laterally of the device beyond the stationary wall members, each said panel of the said end closure units also having a channel and a pad supporting and aligning the channel with a channel member of a stationary wall member and which channels of the panels telescope within the channel members of the stationary wall members and which channels of the panels form support means for the stationary wall members, and cooperable but separate drive means for effecting lateral movement of the panels and channels of one said end closure unit independently of the other end closure unit relative to the stationary wall members and the channel members, the said cooperable but separate drive means including in association with each of the telescoping channels and channel members cooperating relatively movable elements, one of which is carried by a stationary wall member and the other of which is carried by a panel of the said end closure unit, and means interconnecting the separate drive means for effecting movement of the cooperable but separate drive means in unison.

5. In a paving material dispensing device which is adjustable laterally for regulating the width of a dispensing material, the structure comprising, forward and rearward stationary wall members extending laterally of the device in spaced-apart relation, hopper end closure units having panels telescoped on the stationary wall members at each end thereof forming with the stationary wall members a hopper, means supporting the hopper above ground level, said means being secured to the end closure units in supporting relation therewith, an outer channel on the forward stationary wall member on the outer hopper side and extending laterally of the device substantially the full length of the stationary wall member, an outer channel on the rearward stationary wall member on the outer hopper side and extending laterally of the device substantially the full length of the rearward stationary wall member, the said panels of the said end closure units being slidable on the inner side of the stationary wall members laterally of the device and each panel of the said end closure units having an extremity extending laterally of the device beyond the stationary wall members, each said panel of the said end closure units also having a channel and a pad supporting and aligning the channel with a channel member of a stationary wall member and which channels of the panels telescope within the channel members of the stationary wall members and which channels of the panels form support means for the stationary wall members, and cooperable but separate drive means for effecting lateral movement of the panels and channels of one said end closure unit

independently of the other end closure unit relative to the stationary wall members and the channel members, the said cooperable but separate drive means including in association with each of the telescoping channels and channel members a cooperating screw and nut one of which is carried by a stationary wall member and the other of which is carried by a panel of the said end closure unit, and means interconnecting the separate drive means for effecting movement of the cooperable but separate drive means in unison.
